Attorneys.

UNITED STATES PATENT OFFICE.

GEORGE S. WITHAM, JR., OF AU SABLE FORKS, NEW YORK, ASSIGNOR TO GUSTAVUS A. SCHANZE, OF CLEVELAND, OHIO.

SAFETY-INDICATOR FOR INTERNAL-COMBUSTION ENGINES.

1,399,534.

Specification of Letters Patent.

Patented Dec. 6, 1921.

Application filed March 25, 1916. Serial No. 86,577.

To all whom it may concern:

Be it known that I, GEORGE S. WITHAM, Jr., a citizen of the United States, residing at Au Sable Forks, county of Essex, and 5 State of New York, have invented certain new and useful Improvements in Safety-Indicators for Internal-Combustion Engines; and I do hereby declare the following to be a full, clear, and exact description of the invention, such as will enable others skilled in 10 the art to which it appertains to make and use the same.

This invention relates to a safety indicating device for internal combustion engines of the type employed in self-propelled vehicles, such as automobiles, aeroplanes, motor boats, etc.

Engines of this type are provided with circulatory lubricating systems and it is important 20 that the driver of the vehicle be apprised at all times of the conditions of flow and temperature of this system.

The novel safety indicating device of the present invention comprises an improved 25 construction for indicating in an automatic and continuous manner and at a point distant from the engine the above-named conditions of the circulatory system.

The invention will be described more particularly 30 in connection with the embodiments thereof illustrated in the accompanying drawings, but it will be understood that the invention is illustrated by, but not limited to, these specific embodiments.

35 In the accompanying drawings—

Figure 1 shows in elevation and partly in diagram an automobile engine with the invention embodied therein;

Fig. 2 is a view of the face of the thermal 40 indicating instrument;

Fig. 3 is a cross-section of this instrument upon the line 3—3 of Fig. 2;

Fig. 4 is a cross-section upon the line 4—4 of Fig. 2;

Fig. 5 is a view of the face of another embodiment of the invention; and

Fig. 6 is a view partly in section along the line 6—6 of Fig. 5.

Referring to the drawings, in which similar 50 reference characters refer to similar parts throughout the several views thereof, Fig. 1 illustrates an internal combustion engine of any suitable construction as applied to an automobile. It is shown as made up of cylinders 1 and crank case 2 suitably

inclosed within a hood 3. A radiator for the cooling liquid is indicated at 4. It communicates with the cylinder jackets through pipes 5, and 6, there being a pump of any well known construction for maintaining 60 the circulation of the liquid.

The crank case 2 is provided with any suitable lubricating system in which the flow of oil is maintained by a pump 7 having an inlet opening at the bottom of the crank 65 case and a discharge pipe 8 near the top of the case. From the pipe 8 there is tapped off a small branch pipe 9 leading to the indicating instruments upon the dash board 10 of the vehicle. It will be understood, of 70 course, that the indicating instrument may be variously arranged wherever it may be convenient for observation and that the arrangement will also depend upon the nature of the vehicle.

As shown herein, the pipe 9 leads to a coupling 11 from which there is a branch 12 leading to one indicator or gage 13 and a second branch 14 leading to another indicator or gage 15. In the branch 14 is interposed a valve 16 and from the indicator 15 a return pipe 17 leads back to the crank casting or other appropriate part of the engine.

The indicator 13 is in the nature of a pressure gage adapted to indicate the condition of flow of the oil by the pressure thereof produced by the circulatory pump. If for any reason circulation stops, the gage will immediately indicate this fact. (As gages of this type of construction are well known, 85 it is unnecessary to further illustrate or describe the same.)

15 designates the thermal indicator of the invention and the form illustrated in Fig. 1 is shown in detail in Figs. 2, 3 and 4. As 95 appears from these figures the instrument comprises a casing 20 within which is mounted a thermometer 21, the bulb of the latter being contained within an enlargement at the bottom of the casing. The 100 thermometer may be retained within the casing in any convenient manner. In order that indications of the thermometer may be observed, the casing is provided with a sight opening 22, covered by a glass plate 105 23 retained in place upon the casing by a plate 24 upon which may be engraved the scale of the instrument. At the rear of the casing and near the bottom thereof are provided two apertures 25 and 26 by means 110

of which the circulation of oil about the bulb of the thermometer is permitted. These apertures are surrounded with screw-threaded projections 27.

5 One convenient mode of connecting the pipes 14 and 17 to the casing is shown in section in Fig. 3 which illustrates the connection of the latter pipe. This pipe has attached to its end an enlargement 28 formed with a conical front face to engage a corresponding face at the outer edge of 27, and also having a shoulder about which is passed a clamping nut 29 threaded upon 27, after the manner of well known pipe 15 couplings.

It will be understood, of course, that instead of the construction described above, any other convenient mode of attaching the oil pipes to the casing of the thermometer 20 may be used.

In the use of this instrument, as illustrated, 25 is the inlet port and 26 the outlet port, the oil flowing upward around the bulb of the thermometer, but the operation 25 remains the same if the flow is reversed. As this oil is under pressure, there will be a tendency for it to pass upward around the stem of the thermometer, and to prevent this a bushing or washer 31 should be placed 30 around the stem of the thermometer immediately above the aperture 26.

In order that the thermometer may be attached to the dash board without projecting any considerable distance in front of 35 the same, the casing is provided with lugs 30 by means of which it may be screwed to the back of the board, as shown most clearly in Fig. 3. The entire instrument should preferably be of a thickness corresponding 40 approximately to that of the dash board or instrument board so that when in place the instrument will project only a slight distance above the top surface of the board.

45 In Figs. 5 and 6 another form of thermal indicator has been shown. In this embodiment of the invention there is a casing 40 having a tubular extension 41 near the bottom thereof for receiving the bulb of a thermometer 42. The thermometer may be of 50 any desired construction and is preferably so arranged that it may be easily detached from the casing 40 as by a thread projection 43. At the rear of the casing 40 are screw-threaded extensions 44 to which the tubes 14 and 17 may be connected by means of the coupling hereinbefore described, or in 55 any other convenient manner. Thermometer 42 is so related to the casing 40 in the 60 construction illustrated that the bulb of the former comes directly below the channel 45 in the casing. It will be convenient to place the bulb within the aperture of projection 44, where the bulb will be directly in the 65 path of the oil flowing through the device.

A suitable bushing or washer 46 may be provided to prevent the oil from flowing into the thermometer casing and coupling 43.

The casing 40 is formed so that it may be attached to the instrument board of a 70 vehicle in any convenient manner. Even with this arrangement the thermometer will project only a slight distance above the board, and if desired, the construction may be arranged so that the upright portion of 75 the tube of the thermometer comes upon one side of the instrument board, while casing 40 and the pipe connections, are upon the other side of the board.

Having described the construction of an 80 apparatus embodying my invention, the operation thereof may be briefly reviewed.

If the engine is running, pump 7 should maintain a flow of oil from bottom to top of the crank case, and there will be a certain 85 pressure of oil in pipe 8 and branch pipe 9 leading therefrom. So long as this pressure is maintained, the gage 13 will indicate that the oil is being properly circulated. There are many abnormal conditions within the 90 lubricating system, or sufficiently related thereto as to be indicated thereby, which would not be shown by the gage 13. These conditions are particularly due to abnormal increase in temperature. A low 95 grade of oil, an insufficient amount of oil, low water in the radiator, with resulting over-heating thereof, hot bearings, dirty spark plugs, and over-working of the engine, are some of the abnormal conditions which 100 result in over-heating of the oil and may thereby give indication of their existence. By the provision of the thermal indicator 15, the driver of the vehicle has before him at all times a means for indicating the existence 105 of any of these abnormal conditions.

The valve 16 controlling passage of oil to the thermal indicator will under normal conditions of use be open, but if for any reason it is desired to shut off the supply of oil to 110 the latter, it can be easily done by simply manipulating this valve.

There is thus provided, according to the present invention, a mechanism which will indicate in a continuous and automatic manner both the thermal and the flow conditions of the circulatory system, thereby serving to protect the engine against accidental injury due to the various causes enumerated. 115

The indicator or gage 15 enables the operator to tell at a glance whether the oil has been over-heated or whether it is of normal temperature. The indicator or gage 13 shows the operator whether the lubricating pump is operating properly with the necessary amount of oil. The combination of the two indicators gives to the operator a complete and automatic indication which enables him to tell whether the oil is being properly circulated in the right amount and 120 125 130

whether the temperature of this oil is high or low. High temperatures indicate abnormal conditions which require investigation. It is important that both the circulation of 5 the oil and its temperature should be indicated for the reason that either indication alone would not indicate all of the conditions which are necessary to be present for satisfactory operation. Without the ther-

10 mal indicator the oil might be highly overheated without warning of a nature which the operator would heed. Without the indicator of the oil circulation, the thermal indicator might indicate the temperature of 15 the casing when no oil were present. The two indicating devices coact to give a complete indication such as cannot be obtained with either device alone.

Various modifications or changes in the 20 details of construction of my invention may be made without limiting the scope of the same or departing from the principle thereof.

I claim:—

25 1. A device of the character described, comprising in combination, an internal combustion engine, a lubricating system there-

for, including a pump, a gage for indicating fluid pressure, a pipe connection between said system and said gage, a thermometer 30 mounted adjacent said gage, a separate casing for said thermometer, a pipe leading from said connection to said casing, a valve in said pipe and a return pipe leading from said casing to said system; substantially as 35 described.

2. A thermal indicating device for use in connection with the circulatory systems of internal combustion engines, comprising a unitary casing having an elongated central 40 passage formed with an enlarged chamber at the lower end thereof, a thermometer within said passage with its bulb in said chamber, an aperture in the wall of said casing adjacent the upper end of said chamber, a second aperture in said casing near the bottom of said chamber and means surrounding said apertures whereby said casing may be connected to pipes leading to the circulatory system; substantially as de- 45 scribed.

In testimony whereof I affix my signature.

GEORGE S. WITHAM, JR.
